UNITED STATES PATENT OFFICE.

GEORGE WILLIAM BLAKE AND CHARLES EDWARD SHELDON, OF BIGGLESWADE,
ENGLAND.

JOINTING COMPOSITION.

No Drawing.

Application filed February 5, 1923. Serial No. 617,114.

To all whom it may concern:

Be it known that we, GEORGE WILLIAM BLAKE and CHARLES EDWARD SHELDON, subjects of the King of Great Britain and Ireland, and residing at, respectively, the Royal Ash and 31 London Road, both in Biggleswade, Bedfordshire, England, have invented a new and useful Improvement in Jointing Composition, of which the following is a specification.

Our invention relates to a composition for application to the joints of automobile engines and is particularly intended to be applied to the gaskets used for making the joints between the cylinder head and cylinder block of internal combustion engines and other similar joints. These gaskets which are frequently made up of copper and asbestos, are often of a complicated form and expensive to replace, and owing to the large area over which the joints extend, considerable difficulty is found in making an effective joint free from leakage.

Our invention comprises a composition adapted to be applied to the surface of such gaskets so as to make an effective joint between the cylinder head and cylinder block or other parts. At the same time the composition will enable the joint to be readily separated when desired without damaging the gasket, which will come away quite easily from the parts, and may be used again as frequently as desired.

According to this invention we employ a composition of soft soap and French chalk mixed together to the consistency of a paste. This composition is applied thinly over the whole surface of the gasket or the joint to

be made, and the parts are then placed together and bolted up in the usual manner. The composition will render the joint effective and leakproof and is particularly efficient in enabling a good joint to be made between the cylinder head and cylinder block of internal combustion engines employing petrol or like volatile fuel.

The soft soap and French chalk are mixed together in the proportion of approximately 10 parts of soft soap to one part of French chalk by weight. The paste so formed may be then placed in tins or other suitable receptacles for sale and is ready for immediate application to any joint to be made.

Instead of French chalk any other suitable powder or fibrous material may be added to the soft soap in a suitable proportion to form a paste of the required consistency. Another suitable material for this purpose may comprise fine asbestos in a powdered or fibrous state. Asbestos is of a heat resisting nature and will form a permanent joint and assist in retaining the soft soap in place in the interstices, between the gasket and the top of the cylinder head and cylinder block, or other parts upon which it is used.

We claim:

A composition for application to joints of automobile engines comprising a mixture of soft soap and French chalk in the proportion of approximately 10 parts of soft soap to one part of French chalk by weight.

GEORGE WILLIAM BLAKE.
CHARLES EDWARD SHELDON.
